UNITED STATES PATENT OFFICE

ALBERT B. PHISTER AND BENJAMIN H. PHISTER, OF FORT THOMAS, KENTUCKY, ASSIGNORS TO THE PHISTER MANUFACTURING COMPANY, OF CINCINNATI, OHIO, A CORPORATION OF DELAWARE

FIRE EXTINGUISHING APPARATUS

Application filed December 15, 1928. Serial No. 326,273.

Our invention relates to fire extinguishing apparatus, and to an enclosing cabinet for the apparatus which may be permanently incorporated in a building structure.

5 It is the object of our invention to provide a cabinet retaining a water hose preferably permanently coupled to a water pipe in the house service system, in which the hose is mounted on a reel so arranged in the casing 10 that the hose may be withdrawn in any direction within substantially an angle of one hundred and eighty degrees. It is further our object to provide a mounting for a reel which will enable anyone to open the casing 15 or cabinet lid, and then move quickly in the direction in which the hose is required to extinguish the fire without stopping to adjust the position of the reel or to reel off a desired amount of hose and then proceed to 20 use it.

The above and other objects to which reference will be made in the ensuing disclosure we accomplish by that certain combination and arrangement of parts of which we have 25 shown a preferred embodiment.

Referring to the drawing:—

Figure 1 is a front elevation of our preferred type of cabinet.

Figure 2 is a sectional view of the cabinet 30 taken from the position indicated by the line A—A in Figure 1 with the reel swivel bracket so extended that the hose may be withdrawn to the right.

Figure 3 is a sectional view of the cabinet 35 taken from the same position as Figure 2 with the reel extended straight out.

Figure 4 is a sectional view of the cabinet taken from the same position as Figures 2 and 3 with the reel extended so that the hose may 40 be withdrawn to the left.

Figure 5 is a detail view of the reel mounting.

The cabinet will ordinarily be of metal having the sides and ends formed of frame pieces 45 1 having inturned flanged walls 2. The frame may be of desired size but usually will be of such size that it will fit between the studding in the building walls. The back wall of the cabinet is indicated at 1a. One corner of the cabinet will be provided, under normal cir-

cumstances, with an offset portion having walls 3 which form a compartment through which the house service water pipe, such as is indicated at 4, may extend. An elbow 5 or 55 T will be so located in the compartment and so exposed through a hole in the wall 3 as to be available for the attachment of a short nipple to which is connected the water valve 6 having a handle 7 exposed for manipulation from the front of the cabinet. 60

An elbow 8 with a coupling piece 9 will be connected to the valve and the hose will be coupled on the coupling piece as indicated at 10, and left normally in coupled up position so as to be immediately available for withdrawal in case of fire. The reel 11 on which the hose will be mounted has a central axle 12 mounted in forked arms 13 which extend diagonally in the cabinet from a supporting member 14. The member 14 has a shaft 15 which extends through a hole 16 in a link arm 17, being secured rotatably thereon by means of a cotter pin or the like. The link arm 17 at its other end has a hole 18 through which a threaded stud 19, having an enlarged 70 head 20 extends. The stud 19 is secured in a supporting bracket 21 which is mounted on the inturned wall of the frame being secured thereon with bolts 22 or rivets. The link arm 17 has a boss 23 which, when the reel is withdrawn from the cabinet, and turned, engages a boss 24 or blocking member on the support 21. Another boss 24a prevents the reel from being pushed too far into the cabinet. 75

The link is thus pivotally mounted at both its ends, and with the withdrawal of the reel, its pivot is swung clear of the face of the cabinet where it may be swiveled through an arc of approximately one hundred and eighty degrees. The object of preventing the complete swiveling of the link about the axis of the stud 19 is to prevent the reel from jamming in the cabinet. 80 90

The cabinet has a hinged lid or cover 25 which preferably will allow the cover to swing to a completely open position as indicated. The reel when withdrawn may be moved into any of the three positions indicated in Figures 2 to 4, or at any angles between the positions 95 100

illustrated. Thus, no matter in what direction it is required to withdraw the hose from the reel, the reel will quickly adjust itself so as to permit such withdrawal.

6 While the use of hoses mounted on reels for fire protection is not in itself novel, we are unaware of any construction in which such instant availability of a fire hose is provided in a cabinet in which the entire apparatus is normally concealed from view, and
10 is flush with the wall.

The front panel or cover of the cabinet may be used to form a mirror support, or it may be plastered or papered like the walls of
15 the house. It may further be enameled or decorated to match the woodwork or trim. The offset corner, being particularly adaptable for house installation during the construction of the house, we consider within
20 the scope of our invention. We further may vary the particular mounting arrangement which permits the pivot for the reel to be swung clear of the face of the cabinet during the hose withdrawal.

25 Having thus described our invention, what we claim as new and desire to secure by Letters Patent, is:—

30 Fire extinguishing apparatus comprising a wall cabinet having a hose reel, a pivotally mounted support for said reel, and mounting means for said pivotal support which will permit the movement of the pivot of said support from within said cabinet so that said reel will swing to any desired position within
35 an arc of substantially 180° with reference to the face of said cabinet, and means for limiting the pivotal movement of said support.

ALBERT B. PHISTER.
BENJAMIN H. PHISTER.
